WILLIAM F. BOSSERT, OF UTICA, NEW YORK, ASSIGNOR OF ONE-THIRD TO
HENRY P. CROUSE, OF UTICA, NEW YORK.

THREE-WAY RAILWAY-SWITCH.

SPECIFICATION forming part of Letters Patent No. 690,922, dated January 14, 1902.

Application filed September 20, 1901. Serial No. 75,782. (No model.)

To all whom it may concern:

Be it known that I, WILLIAM F. BOSSERT, residing at Utica, in the county of Oneida and State of New York, have invented certain Improvements in Three-Way Railway-Switches, of which the following is a specification.

The invention about to be described relates to railroad-switches, by means of which cars are diverted from one pair of rails to another. In such switches it is common to provide a switch for each diversion from one track to another, and it is less common to arrange two or more switches to be operated by the same mechanism to enable cars to be transferred from a main track to a plurality of diverging tracks.

By means of the present invention I am enabled to switch from the main track to a number of others by the same mechanism operated in a continuous direction or in any desired direction, as I will now proceed to describe, and particularly point out in the appended claims.

Of the accompanying drawings, which form a part of and illustrate this specification, Figures 1, 2, and 3 are diagram views of a main railroad-track having a divergent track on each side thereof, showing the main track switched to each side track, respectively. Fig. 4 is a sectional view of the switch apparatus, and Figs. 5 and 6 are details of the foregoing. Fig. 7 is a sectional view of the switch-lantern.

I have illustrated the invention with a three-way switch, and in the drawings A represents a main track, consisting of the rails a^1 and a^2 , both of which, as they approach the switch S, are bent outwardly, as b^1 and c^2 , to form respective parts or rails of the divergent tracks B and C—one to the left side and the other to the right side. The main track continues by the rails a^3 and a^4 , but between the rails a^1 and a^2 is a movable part or point a^3 , pivoted at a^4 , and between the rails a^3 and a^4 is the movable part or point a^5 , pivoted at a^6 . The second rail b^2 of the track B has a movable terminal point b^3 , pivoted at b^4 and is joined with the rail c (the complementary rail of track C) at its junction f therewith. S is the switch, shown as having a hollow supporting-casing m , provided at its base

with feet 20, by which it is bolted to a suitable foundation. 11 and 12 are divisions from side to side of the casing, in the center of which is a square hole adapted to receive and support the vertical square rod s , provided with a collar 25, which rests upon the top of the division 11 to hold the rod in position. Secured to the lower end of the rod is a disk j . At the upper end of the rod s is a six-sided lantern p , having orifices on each side, covered with glass of three differing colors, the opposite orifices having similar colors, and directly below the lantern is a block o , having sides corresponding to those of the lantern and in the same plane. The sides of the block are painted to the same color as the glass windows directly above them.

r is a lamp inside the lantern, which has a cover to protect the lamp.

D is a lever pivoted at 16 to the rod s and has a slot in its lower end adapted to fit over the lugs n , n^2 , and n^3 , projecting outwardly from the upper end of the casing, and 17 is a link pivoted to the lever D at 15 at one end, while its opposite end is pivoted to the sliding six-sided wedge-block 14, whose lower end is tapered to readily engage the entrance of the six-sided hole in the top 13 of the casing, which hole serves as a locking-nut and prevents the rod s from turning around.

i is a rod extending from the movable point a^3 to the movable point b^3 and is connected by the collars 3 3 with the former and by the collars 4 4 with the latter.

h is a flat bar extending under the rod i and under the rails, provided with an upward-projecting lug 9, through which passes the rod i , and on each side of the lug are collars 10 10, secured to the rod to hold the lug 90 in position. At one side of the bar h is pivoted a link 5, whose other end is pivoted to the upper side of the disk j at point 8, and h^2 is a similar flat bar extending under the rod i^2 and under the rails with an upward-projecting lug 9 ^{a} , through which the rod a^2 passes, secured in position by collars 10 10. One end of the link 6 is pivoted to the bar and its opposite end is pivoted to the under side of the disk j .

In the operation of the invention to show the progressive travel of the switch S we ob-

serve that Fig. 1 represents the main track A as having its rails a a^2 severed at the switch and that all the movable points a^3 , c^3 , b^3 , and a^9 are drawn over to the right, the links 5 and 6 having been pulled as far as they can go by the turning of the lever D to the position shown in dotted lines, so that the rail a continues to rail b of track B, and the rail a^2 is continued over the movable point b^3 and rail b^2 of said track. While in this position the lantern-signal p and the target-signal o are turned so that the colors thereon indicate to the switchman the position of the switch. Should it be desirable to continue the track 15 A in a straight line, the lever D is raised, as shown in Fig. 5, so that the six-sided sleeve 14 is raised and unlocked from the nut 13. Then the lever is moved over the lug n^2 and closed down upon the same, the sleeve 14 being forced into the nut 13, locking the lever thereto. When the lever D is moved over, the disk is rotated, and the link 5 forces the bar h , with its rod i , into the position shown in Fig. 2, and the movable point b^3 is carried away from the movable point a^9 , and the movable point a^3 is separated from the movable point c^3 and carried over to the rail a . The link 6 is carried from one side of the center of the vertical rod s to a similar position on the other side of the center, so that practically there is no movement of the bar h^2 and its connected rod i^2 , there being sufficient allowance made in construction to regulate this, and should the track A be connected to the divergent track C in effecting this the lever D is raised and turned to the position shown in Fig. 3 and locked with the lug n^3 . This movement rotates the disk j and forces the link 6 into the position shown in 40 said figure, and the bar h^2 , with its rod i^2 , carries the movable points a^9 and c^3 , the former away from the rail a^2 into contact with the movable point b^3 and the latter into contact with the movable point a^3 , and in this case 45 the disk j carries its pivoted end of the link 5 from one side of the center of the rod s to a similar position on the other side of the center, and as in the similar position of the link 6 the parts are so arranged that there is no 50 movement of the bar h . At each movement of the lever D and the consequent rotation of the lantern-signal and the target-signal, the former being more especially a night and the latter a day signal, a colored window and surface are exposed, which are characteristic 55 of the position of the switch and are indications to the railway employees of such positions.

I claim as my invention—

60 1. In a three-way railway-switch, a main track and a divergent track from each side thereof, the two rails of the main track being severed at the switch and movable points introduced on one side, while on the other side 65 the rails extend outwardly to form one entrance-rail of the respective divergent tracks, the second entrance-rails of the divergent

tracks terminating in movable points adjacent to the main-track-rail movable points and inside the same, the movable point of one 70 main rail rigidly connected by a bar with the movable point of a rail of a divergent track on one side, and the second main-rail movable point connected rigidly by a bar with the movable point of a rail of the second divergent 75 track, a switch consisting of a casing supporting a vertical rod bearing upon its lower end a disk, two links, one pivoted at the upper side of the disk and also to the connecting rail-bar of one divergent track, and the second link pivoted at the lower side of the disk and also with the connecting rail-bar of the second divergent track, a lever pivoted to 80 said vertical rod and linked to a sliding sleeve on said rod, which sleeve normally rests in a 85 nut in said casing, while the lever is locked to one of three studs upon the said casing.

2. In a three-way railway-switch, a main track and a divergent track from each side thereof, the two rails of the main track being 90 severed at the switch and movable points introduced on one side, while on the other side the rails extend outwardly to form one entrance-rail of the respective divergent tracks, the second entrance-rails of the divergent 95 tracks terminating in movable points adjacent to the main-track-rail movable points and inside the same, the movable point of one main rail rigidly connected by a bar with the movable point of a rail of a divergent track 100 on one side, and the second main-rail movable point connected rigidly by a bar with the movable point of a rail of the second divergent track, a switch consisting of a casing supporting a vertical rod bearing upon its 105 lower end a disk, two links, one pivoted at the upper side of the disk and also to the connecting rail-bar of one divergent track, and the second link pivoted at the lower side of the disk and also with the connecting rail-bar 110 of the second divergent track, a lever pivoted to said vertical rod and linked to a sliding sleeve on said rod, which sleeve normally rests in a nut in said casing, while the lever is locked to one of three studs upon the said 115 casing, a signal-lantern at the upper end of said vertical rod having six sides, each provided with differently-colored transparent windows, the opposite windows having the same colors, with means for illuminating the same, a second or target signal under the lantern, having six sides each colored the same as the window above it.

3. In a three-way railway-switch, a main track and a divergent track from each side 125 thereof, the two rails of the main track being severed at the switch and movable points introduced on one side, while on the other side the rails extend outwardly to form one entrance-rail of the respective divergent tracks, the second entrance-rails of the divergent 130 tracks terminating in movable points adjacent to the main-track-rail movable points and inside the same, the movable point of one

main rail rigidly connected by a bar with the movable point of a rail of a divergent track on one side, and the second main-rail movable point connected rigidly by a bar with the 5 movable point of a rail of the second divergent track, a switch consisting of a casing supporting a vertical rod bearing upon its lower end a disk, two links, one pivoted at the upper side of the disk and also to the connecting rail-bar of one divergent track, and the second link pivoted at the lower side of the disk and also with the connecting rail-bar of the second divergent track, a lever pivoted to said vertical rod and linked to a sliding 10 sleeve on said rod, which sleeve normally rests in a nut in said casing, while the lever is locked to one of three studs upon the said casing, whereby when the main track may be switched to one divergent track then to close 15 its own track, and finally switched to the second divergent track, by successively turning the switch-lever in the same direction.

4. In a three-way railway-switch, a main track and a divergent track from each side thereof, the two rails of the main track being 20 severed at the switch and movable points introduced on one side, while on the other side the rails extend outwardly to form one entrance-rail of the respective divergent tracks, the second entrance-rails of the divergent 25 tracks terminating in movable points adjacent to the main-track-rail movable points and inside the same, the movable point of one main rail rigidly connected by a bar with the movable point of a rail of a divergent 30 track on one side, an operating-rod extending parallel with the said bar under the rails provided with adjustable means of attachment to the said bar and having a link pivoted to one end; and the second main-rail 35 movable point connected rigidly by a bar with the movable point of a rail of the second divergent track, a switch consisting of a casing supporting a vertical rod bearing upon its lower end a disk, two links, one pivoted at the upper side of the disk and also to the connecting rail-bar of one divergent track, and the second link pivoted at the lower side of 40 the disk and also with the connecting rail-bar of the second divergent track, a lever pivoted to said vertical rod and linked to a sliding sleeve on said rod, which sleeve normally rests in a nut in said casing, while the lever is locked to one of three studs upon the said 45 casing, whereby when the main track may be switched to one divergent track then to close its own track, and finally switched to the second divergent track, by successively turning the switch-lever in the same direction, and as 50 the movable points connect with the severed main track to form a completed track, a signal is automatically made for each track.

5. In a railway-switch consisting of a main 55 track and a divergent track from each side

thereof, the rails of the main track bending outward on each side to form approaches for a rail of each divergent track, severing the main-track rails, each of which is adapted to be closed by pivoted movable points from the 65 rail continuations; the second rails of each divergent track meeting at a junction between the main-track rails and provided with pivoted movable points; each main-track movable point rigidly connected to the movable point of the divergent-track rail adjacent thereto by a rod which is in flexible connection with a disk on the end of a vertical rod located in suitable bearings; with means for rotating the said disk and for locking the 70 same to hold the said movable points in any one of three positions.

6. In a three-way railway-switch, a main track and a divergent track from each side thereof, the two rails of the main track being 75 severed at the switch and movable points introduced on one side, while on the other side the rails extend outwardly to form an entrance-rail of the respective divergent tracks, the second entrance-rails of the divergent 80 tracks terminating in movable points adjacent to the main-track-rail movable points and inside the same, the movable point of one main rail rigidly connected by a bar with the movable point of a rail of a divergent 85 track on one side, an operating-rod extending parallel with the said bar under the rails provided with adjustable means of attachment to the said bar and having a link pivoted to one end; and the second main-rail 90 movable point connected rigidly by a bar with the movable point of a rail of the second divergent track, an operating-rod extending parallel with the said bar under the rails provided with adjustable means of attachment 95 to the said bar and having a link pivoted to one end; a switch consisting of a casing supporting a vertical rod bearing upon its lower end a disk, one of said links pivoted at the upper side of the disk, and the second link 100 pivoted at the lower side of the disk; a lever pivoted to the said vertical rod and linked to a sliding sleeve on said rod; which sleeve normally rests in a nut in said casing, while the lever is locked to one of three studs upon 105 the casing.

In testimony whereof I have signed my name to this specification, in the presence of two subscribing witnesses, this 3d day of September, 1901.

WILLIAM F. BOSSERT.
